CLAIM

The ornamental design for a vaping device, as shown and described.

DESCRIPTION

FIG. 1 is a top perspective view of a new design for a vaping device.

FIG. 2 is a bottom perspective view of a new design for a vaping device.

FIG. 3 is a left side view of the vaping device of FIG. 1.

FIG. 4 is a right side view of the vaping device of FIG. 1.

FIG. 5 is a front view of the vaping device of FIG. 1.

FIG. 6 is a back view of the vaping device of FIG. 1.

FIG. 7 is a top view of the vaping device of FIG. 1; and, FIG. 8 is a bottom view of the vaping device of FIG. 1.

The broken lines in the drawings depict portions of the vaping device that form no part of the claimed design.
